(57) **CLAIM**

The ornamental design for a display screen or portion thereof with a sequential graphical user interface, as shown and described.

DESCRIPTION

FIG. 1 is a front view of a display screen or portion thereof with a sequential graphical user interface showing a first image in a sequence according to a first embodiment of the ornamental design;

FIG. 2 is a second image in the sequence according to the first embodiment of the ornamental design;

FIG. 3 is a third image in the sequence according to the first embodiment of the ornamental design;

FIG. 4 is a front view of a display screen or portion thereof with a sequential graphical user interface showing a first image in a sequence according to a second embodiment of the ornamental design;

FIG. 5 is a second image in the sequence according to the second embodiment of the ornamental design; and, FIG. 6 is a third image in the sequence according to the

FIG. 5 is a third image in the sequence according to the second embodiment of the ornamental design. The broken lines showing a portion of a display screen, text,

The following portion of a reply brief, etc., and other images are included for the purpose of showing portions of the article that form no part of the claimed design. The appearance of the transitional image sequentially transitions between the images shown in FIGS. 1-3 and 4-6. The process or period in which one image transitions to another image forms no part of the claimed design.

1 Claim, 6 Drawing Sheets

Related U.S. Application Data

continuation of application No. 29/612,156, filed on Jul. 28, 2017, now Pat. No. Des. 844,649.
